FLUID ACTUATED TOOL

Earl B. Lear, Garfield Heights, Ohio, assignor to
The Cleveland Pneumatic Tool Company,
Cleveland, Ohio, a corporation of Ohio

Application September 8, 1939, Serial No. 294,002

5 Claims. (Cl. 121—35)

This invention relates broadly to fluid actuated tools generally, but more particularly to fluid actuated riveting hammers of the type used for upsetting rivets made of relatively soft material such as aluminum. Still more particularly, this invention deals with the provision of valve means for controlling the amount of motive fluid admitted to the tool irrespective of the throttle valve normally controlling the operation of the tool.

- 10 In the manufacture of airplanes or the like, wherein aluminum rivets are used in great quantities, it is often necessary to upset series of rivets of different sizes. Heretofore, the practice followed was for an operator to upset all the rivets 15 irrespective of the size thereof, with one riveting hammer or gun of a size and capacity capable of upsetting the largest rivets. Since the use of the maximum upsetting power of the gun on smaller rivets tended to squash the rivets in a manner 20 contrary to the standard requirements, it was necessary for the operator, when upsetting smaller rivets, to reduce the power of the gun by operating the same with a partly open throttle valve. The throttle valve of such tools being generally 25 actuated by a finger operated trigger-like lever, it was difficult for the operator to maintain the throttle in the desired partly open position, consequently causing the upsetting power of the tool to vary during the upsetting operation and requiring the operator to exercise great precautions 30 in order to prevent over upsetting of the rivets.

It is therefore one object of this invention to provide a riveting hammer with valve means for selectively controlling the maximum amount of 35 motive fluid which may be admitted to the tool, while enabling its throttle valve to be moved and maintained in a fully open position.

Another object of this invention is to provide a riveting gun with a novel motive fluid inlet controlling valve forming a compact assembly which is strong, durable and efficient.

Other objects and advantages more ancillary to the foregoing reside in the specific construction and aggroupment of the elements peculiar 45 to this structure, as will become apparent from a more complete examination of this specification.

In the drawing:

Fig. 1 is a side elevational view of a riveting hammer embodying the invention, the handle being partly broken away to show details of construction.

Fig. 2 is an enlarged view of the portion of the handle shown in section in Fig. 1.

Fig. 3 is a view similar to Fig. 2 showing the 55 valve in another position.

Fig. 4 is an enlarged longitudinal sectional view taken in a plane indicated by line 4—4 in Fig. 1.

Fig. 5 is an enlarged cross sectional view taken in a plane indicated by line 5—5 in Fig. 1. 5

Fig. 6 is an end view looking in the direction of the arrows 6—6 in Fig. 3.

Referring to the drawing, 10 represents a riveting hammer including a cylinder 11 having a piston (not shown) reciprocable therein and actuated on a rivet set 12, which is operatively mounted within a front end of the cylinder 11 and secured in position by a suitable retainer 13. To the cylinder 11 is threaded or otherwise affixed a piston-like handle 14 provided, within its upper 15 end, with a longitudinally extending bore 15 opening into an inlet passage 16 which leads through the handle into the cylinder 11 for admitting motive fluid therein effecting the reciprocation of the piston. Leading obliquely from the 20 bore 15, between the ends thereof, there is another inlet passage 17 opening through the upper rear end portion of the handle and having mounted in the outer end thereof a pipe connector 18 in which may be secured the end of a motive fluid 25 supplying conduit (not shown).

Pressed in the bore 15, there is a sleeve or insert 19 formed with a bore 20 extending longitudinally therethrough, and having its inner end communicating with the passage 16. Adjacent its inner 30 end, the bore 20 is provided with an internal shoulder 21 forming a valve seat for a throttle valve 22 slidably mounted within the bore 20. The valve 22 is operable away from the seat 21 by a pin or rod 23 slidable within a bushing 24 35 mounted in the handle 14 coaxially with the bore 15. The inner end of the pin is engaging the adjacent end of the valve 22, while the outer end of the pin is engaged by a trigger-like lever 25 pivotally secured within a handle slot 26 by a 40 cross pin 27.

Also mounted within the bore 20 of the insert 19, there is an auxiliary valve 28 having a threaded shank 29 extending through a bushing 30 screwed within the outer end of the bore 20. 45 This auxiliary valve is held in the bore 20 against rotation relative thereto by a cross pin 31 carried by the bushing 30 and cooperating with a flat 32 formed on the shank 29. This flat is long enough to enable longitudinal movement of the valve 28 50 from substantially the position shown in Fig. 2 to that shown in Fig. 3. Screwed on the shank 32, there is a small knurled wheel 33 held against longitudinal movement relative to the bushing 30 by a spring clip 34 mounted partway in corre- 55

sponding grooves provided in the bushing 30 and on the shank 35 of the wheel 33. Since the wheel 33 is retained against endwise movement and the valve 28 is held against rotation, it will be understood that rotation of the wheel in one or the other direction will effect the longitudinal movement of the valve 28 in the bore 20 of the insert 19. In order to prevent accidental rotation of the wheel 33, there is clamped between the outer end 10 of the insert 19 and the head of the bushing 30, a washer 36 formed with a leaf-like spring 37 extending over the wheel 33 and having its underside provided with a V-shaped protuberance 38 engaging the knurls of the wheel 33.

15 The insert 19 is provided with one radially extending port 39 leading from the passage 17 into the insert bore 20, and adjacent that port with three longitudinally spaced smaller ports 40 leading from the bore 20 into a semicircular longitudinally extending recess 41 provided on the insert 19. At its inner end, the recess 41 is terminated by an annular recess 42 having radial ports 43 leading therefrom into the bore 20 at a place adjacent to the seat 21, which ports together with the recesses 41 and 42, the ports 39 and 40, and the passages 16 and 17 constitute a motive fluid conveying passageway extending through the handle 14. Constantly urging the throttle valve 22 into engagement with its valve seat 21, there is interposed between that throttle valve and the auxiliary valve 28 a compression spring 44.

In the operation, it will be understood that the motive fluid, such as compressed air, admitted into the inlet passage 17 through the connection 35 18 may flow therefrom into the bore 20 via the port 39, and from the bore 20 into the recesses 41 and 42 via the smaller ports 40. With the trigger 25 in the position shown in Fig. 1, the compression spring 44 active on the throttle 40 valve 22 will maintain it in engagement with the valve seat 21 for preventing the flow of the motive fluid past the valve seat 21, thereby preventing supply of the fluid to the hammer. Upon exerting pressure on the trigger 25, the operator will 45 cause its pivotal movement in a counterclockwise direction around the pin 27, and the consequential longitudinal movement of the pin 23 toward the throttle valve 22, thereby compressing the spring 44 for opening the valve relative 50 to its valve seat as clearly shown in Fig. 3. In this instance, the motive fluid admitted into the inner end portion of the bore 20 through the ports 43, is free to flow through the passage 16 into the hammer for effecting the reciprocation of 55 its piston and the consequential delivery of impacts on the rivet set 12 for upsetting the rivet engaged thereby.

When the auxiliary valve 28 is positioned as shown in Fig. 2, that is, at the end of its inward movement, the ports 39 and 40 are almost entirely closed by the valve. In this instance, the amount of motive fluid thus admitted to the cylinder 11 via the recess 42, the ports 43 and the passage 16, is calculated to produce reciprocation 60 of the piston at a relatively slow rate of speed and power, a condition of operation found desirable when upsetting very small rivets made of soft material such as aluminum. When it is desired to upset larger rivets and therefore operate 65 the tool at a greater rate of speed and power, the operator may simply rotate the wheel 33 in a direction causing outward movement of the auxiliary valve 28, thereby resulting in one or more of the ports 40 to be uncovered by the valve 70 for enabling a greater amount of motive fluid to

be admitted to the piston for effecting its reciprocation at a greater rate of speed and power.

From the foregoing description, it will be understood that by rotating the wheel 33, it is possible to move the auxiliary valve 28 into more or less complete open position relative to the passageway extending through the handle 14 or more particularly relative to the ports 39 and 40 forming a part of that passageway, thereby controlling the motive fluid conveying capacity of the 10 inlet passageway while enabling the operator to maintain the trigger 25 in a fully depressed position resulting in the full open position of the throttle valve 22.

Although the foregoing description is necessarily of a detailed character, in order to completely set forth the invention, it is to be understood that the specific terminology is not intended to be restrictive or confining and it is to be further understood that various rearrangements of parts and modifications of structural detail may be resorted to without departing from the scope or spirit of the invention as herein claimed.

I claim:

1. In a handle for fluid actuated tools, a motive fluid conveying passageway, a sleeve in said handle intersecting said passageway, ports through said sleeve enabling conveyance of the motive fluid through said passageway, passageway controlling means including a throttle valve 25 slideable in said sleeve into opened or closed positions relative to said passageway, and an auxiliary slideable valve in said sleeve selectively movable into more or less opened position relative to said ports for controlling the motive fluid conveying capacity of said passageway when said throttle valve is fully opened relative to said passageway.

2. In a handle for fluid actuated tool, an insert, a motive fluid conveying passageway in said handle extending through said insert, means for opening or closing said passageway including a throttle valve slideable in said insert, means independently of said throttle valve for selectively controlling the amount of motive fluid capable of flowing through said passageway when opened by 45 said throttle valve including an auxiliary valve in said insert slideable into more or less open position relative to said passageway, and means for sliding and maintaining said auxiliary valve in the desired position.

3. In a handle for fluid actuated tool, an insert, a motive fluid conveying passageway in said handle extending through said insert, means for opening or closing said passageway including a throttle valve slideable in said insert, a trigger-like lever pivotally carried by said handle operatively associated with said throttle valve for opening the same, means independently of said throttle valve for selectively controlling the amount of motive fluid capable of flowing through 60 said passageway when opened by said throttle valve including an auxiliary valve in said insert disposed coaxially with said throttle valve for movement into more or less open position relative to said passageway, and rotatable means operatively associated with said auxiliary valve operable from the exterior of said handle for effecting movement of said last named valve.

4. In a handle for fluid actuated tools, an insert having a bore extending therethrough, a pair 70 of coaxial valves slideable in said bore, means for effecting slideable movement of one of said valves including a pivotally movable trigger-like lever carried by said handle, a rotatable member exteriorly of said handle operatively associated with 75

the other of said valves for effecting its slideable movement, and ports through said insert controlled by said valves.

5. In a handle for fluid actuated tools, an inlet connection projecting outwardly from said handle, an insert in said handle, an inlet passageway leading from said connection through said insert, a duality of coaxially slideable valves in said insert for controlling said passageway,

means for effecting slideable movement of one of said valves including a pivotally movable trigger-like lever carried by said handle, means for effecting slideable movement of the other of said valves including a rotatable member exteriorly of said handle below said connection, and a lock associated with said member for preventing its accidental rotation. 5

EARL B. LEAR.
